EMERGENCY CUT-OFF FOR AUTOMATIC SPRINKLER SYSTEMS.

1,167,860.

Specification of Letters Patent.

Patented Jan. 11, 1916.

Application filed May 22, 1915. Serial No. 29,901.

To all whom it may concern:

Be it known that we, JOHN T. VAN DILLEN and GEORGE H. F. BERGMANN, citizens of the United States, residing at St. Louis, 5 State of Missouri, have invented certain new and useful Improvements in Emergency Cut-Offs for Automatic Sprinkler Systems, of which the following is a full, clear, and exact description, reference being had to the accompanying drawings, 10 forming a part hereof.

Our invention has relation to improvements in emergency cut-offs for sprinkler heads of automatic sprinkler systems; and 15 it consists in the novel features of construction more fully set forth in the specification and pointed out in the claims.

As well understood in the art, the sprinkler heads of automatic sprinkler systems 20 are equipped with fusible plugs, which in case of fire or a rise in temperature due to fire in the immediate neighborhood of the head, fuse and thereby release a stream of water from the pipe to which the head is attached. Experience has shown that very 25 frequently these plugs deteriorate and disintegrate with time as a result of atmospheric conditions by which the same are surrounded, thereby releasing the water. On 30 other occasions the plug or closure is dislodged by jars due to vibrations of the building from various causes; from the hammering of pipes in making plumbing repairs and the like and from other causes, 35 thereby allowing the water in the pipes to escape into the room and causing considerable damage before it can be shut off at the source of supply.

It is therefore the object of our invention 40 to provide a device which in emergencies such as here referred to, may be used to instantly cut off the flow of water at the sprinkler head before any considerable damage results, and before the main supply valve 45 can be reached and closed. Frequently the exact position of this valve is not known to the occupants of the room; very often the valve sticks so it can not be instantly operated thus allowing the water to flow and 50 damage the premises and any stock stored in the room. By our invention the water may be instantly shut off thereby preventing the evil consequences above pointed out.

A further object of our invention is to 55 provide a cut-off which is simple, one readily applied to a sprinkler-head, one which

is effective, and one possessing further and other advantages better apparent from a detailed description of the invention in connection with the accompanying drawings, 60 in which—

Figure 1 is a side elevation of the cut-off inserted into the loop of a sprinkler head, with parts broken away, the operating wedge being driven inward its full limit; 65 Fig. 2 is a front elevation of Fig. 1; Fig. 3 is a vertical cross-section on the line 3—3 of Fig. 1, the stick or pole being removed; Fig. 4 is a vertical middle longitudinal section on the line 4—4 of Fig. 2 with the 70 wedge however partially withdrawn; Fig. 5 is a similar section with wedge driven inward as shown in Fig. 1; Fig. 6 is a top plan of the lower block with wedge resting thereon; and Fig. 7 is a conventional elevation 75 of a prevailing form of sprinkler head showing the fusible plug.

Referring to the drawings, W represents a short section of a water pipe equipped with T's 1 to which the sprinkler heads are 80 secured, a head usually comprising a discharge nozzle n located within a ring or loop 2, the latter being provided at a point diametrically opposite the nozzle with a spray member or rosette 3, a short teat 4 85 projecting inwardly from within the spray member toward the nozzle n and disposed on the line of the axis of said nozzle. Between the nozzle n and the teat 4, the usual fusible plug P is mounted (Fig. 7). These 90 features are old and well understood in the art.

Referring now specifically to our invention, 5 represents a block or equivalent member substantially oblong in form and flat, 95 the sides thereof being provided with parallel flanges h, h, projecting above what for convenience we shall designate as the upper face of the block, and extending the major portion of the length of the block, the forward ends of the flanges terminating at the base of the tapering end or nose e of the block. At a convenient point rearward of the front ends of the flanges h the block is provided with laterally projecting lugs 6 100 against which the loop 2 of the sprinkler head may shoulder or rest when the device is inserted into the loop. Carried by the lugs 6 and projecting a suitable distance above the block are guide pins 7 which pass 105 freely through openings formed in corresponding lugs or lobes 8 of a complementary

block 9 deposited over the block 5 and spanning the flanges h . Slidably operating over the upper face of the block 5 between the flanges h , h , and confined between the blocks 5 and 9 is a wedge 10, said wedge being provided with a longitudinally disposed slot or opening s one wall of which has disposed thereon a series of rack teeth t with which engages a pinion 11 forming the upper terminal of a rotatable spindle 12 mounted in the socket or hollow boss 13 formed with the block 5, the slot s of the wedge operating across the bore of said boss. The spindle 12 is retained in the socket 13 by a screw 14 whose inner end traverses an annular peripheral groove d formed on the spindle. At a convenient point the spindle is provided with a flange or collar 12' which bears against the free end of the socket 13, said 20 flange carrying a resilient lip or flexed spring 15 operating as a catch and adapted to snap into a shallow depression m on the socket wall for a purpose to presently appear. The outer portion of the spindle 12 is screw-threaded to receive the socket 16 of a suitable stick or pole 17 terminating in an operating handle H if desired. The forward end of the block 9 terminates in a sloping nose e' on the order of the nose e , 25 said nose e' being provided with a longitudinally disposed groove or depression w for the reception and guidance of the teat 4 of the sprinkler head. The front end of the wedge 10 likewise terminates in a sloping nose e'' on the order of the formations e , e' . Formed in the bottom of the block 5, and partly entering or extending into the lugs 6 is a dovetail recess r (extending the width of the block) into which is inserted a compressible layer 18 of rubber or equivalent packing material adapted to close over the mouth of the nozzle n of the sprinkler head when the device is inserted into the loop 2. 30 The operation will now be perfectly clear from the foregoing, and briefly it is substantially as follows: Let us assume that the plug P by accident or otherwise has become dislodged so as to release the water through the nozzle n . The device with the several parts assembled as shown in Figs. 1 and 2 and mounted on the stick 17, is picked up and inserted into the loop 2 (the noses e , e' , being inserted first) until arrested by the loop striking the shoulders formed by the lugs 6. During the insertion the forcible jets or sprays of water issuing from the head impinge against the blocks and unless the latter were held steady by the spring 15, the device might be deflected or swung around on its spindle 12 by such impinging jets and make the insertion thereof into the loop difficult. The spring or catch 15 however imposes just enough friction on the wall of the socket 13 to keep the device steady and prevent displacement thereof while being

inserted. Once the device is inserted, however, the operator gives the stick 17 a turn in proper direction, thus rotating the spindle 12 to which the stick is attached (the spring 15 readily riding out of the shallow 70 depression m when rotation is imposed on the spindle). The pinion 11 at the end of the spindle in turn actuates the wedge 10 through the rack teeth t with which it is in mesh, causing the wedge to be forced inward 75 between the blocks 5, 9, the block 9 being forced against the teat 4, and the block 5 against the nozzle n the opening of which is closed by the packing or compressible layer 18, a water tight joint being thus insured and the water effectively cut off. It may be stated in passing that in the insertion of the blocks into the loop 2, the device is properly guided and centered by the teat 4 riding in the groove w of the movable 80 block 9. Of course, the wedge 10 operates to drive the blocks 5 and 9 apart, but since only one of the blocks, to wit, the block 9 may be said to be the movable one (operating freely along the guide pins 7) the driving of the seat or layer 18 against the nozzle n is merely the effect or result of forcing the block 9 against the teat 4. It is immaterial which block we consider as the movable one and which the stationary; the fact remains 85 that they are movable relatively to one another. Once the water is cut off at the nozzle n in the manner here described, the main valve at the source of supply can be turned to shut off the water, the device removed from the loop 2, and a new fusible plug mounted in position, the whole consuming a minimum amount of time and entailing little damage to the premises. 90

Obviously, the apparatus is susceptible of 105 many changes to which the skilled mechanic may resort without departing from the nature or spirit of the invention.

Having described our invention what we claim is:

1. In combination with a pair of separable members jointly insertible into a loop forming the terminal of a sprinkler head, a slide interposed between the members and operating in a plane transverse to the path of the separating movement of the members to drive the members apart with a movement of the slide in a given direction, and a member about which the separable members are jointly rotatable operating through one of 115 the separable members for actuating the slide.

2. In combination with a pair of separable blocks jointly insertible into a loop forming the terminal of a sprinkler head, said blocks 125 tapering at the forward end, a pair of transversely disposed guide pins on one of the blocks spaced apart and operating freely through openings in the opposite block, a sliding wedge operating between the blocks, 130

and an operating pole having one end traversing one of the blocks for actuating said wedge.

3. In combination with a pair of separable blocks insertible into a loop forming the terminal of a sprinkler head, said blocks tapering at the forward end, a pair of transversely disposed pins on one of the blocks spaced apart and operating freely through openings in the opposite block, a sliding wedge operating between the blocks and provided with a slot having rack teeth disposed on one wall thereof, a pinion engaging the rack, and a rotatable operating pole coupled to the pinion and operating through one of the blocks for rotating the pinion and actuating the wedge.
4. An emergency cut-off for sprinkler heads comprising a pair of blocks insertible into a loop forming the terminal of a sprinkler head, said blocks having contiguous plane faces along which the same are separable, and tapering at one end for ready insertion into said loop, a layer of compressible material on the outer face of one of the blocks for engaging the discharge opening of the sprinkler head and forming a seat for said block, a pair of transversely disposed guide pins leading from the last mentioned block and operating through openings of the opposite block, a sliding wedge between the blocks, provided with a slot elongated in the general direction of movement of said wedge.
5. In an emergency cut-off for sprinkler systems, a pair of blocks insertible into a loop forming the terminal of a sprinkler head, a sliding wedge operating between the blocks, a rotatable member operating through one of the blocks for actuating the wedge, a spring or resilient catch on said rotatable member, the block traversed by said rotatable member being provided with a shallow depression for receiving the catch, whereby accidental rotary displacement of the blocks during the act of insertion is prevented, but rotation of the member is permitted for actuating the member and the wedge controlled thereby.

In testimony whereof we affix our signatures in presence of two witnesses.

JOHN T. VAN DILLEN.

GEORGE H. F. BERGMANN.
